UNITED STATES PATENT OFFICE.

JOSEPH ZEITLIN, OF FULHAM, LONDON, ENGLAND.

INTERNAL-COMBUSTION ENGINE WITH VARIABLE PISTON-STROKES.

Specification of Letters Patent.

Patented Apr. 4, 1914.

1,177,913.

Application filed June 12, 1914. Serial No. 844,695.

To all whom it may concern:

Be it known that I, JOSEPH ZEITLIN, subject of the Czar of Russia, residing at 115 Bishop's Mansions, Fulham, in the county of London, England, have invented new and useful Improvements in Internal-Combustion Engines with Variable Piston-Strokes, of which the following is a specification.

This invention relates to internal combustion engines of the rotating cylinder type, in which there is imparted, in addition to the usual movements of each piston and cylinder an additional relative movement between each piston and its cylinder of such a character as to result in a differential piston stroke, so that for example each piston may be caused to sweep over the usual clearance space upon the exhaust and suction strokes in addition to the space swept over upon the compression and working strokes, thereby insuring complete scavenging, greater suction, a full charge of combustible mixture undiluted with hot products of combustion, and has for its object the arrangement of the various moving parts whereby a perfect balance of the moving parts about the axes of motion of the engine as a whole and its parts is insured.

To carry the invention into effect the requisite additional relative movements of pistons and cylinders are effected by causing the centers of the big ends of the connecting rods to traverse a circular path around the crank pin, by means of an eccentric bush mounted thereon, substantially in the manner which has been proposed for stationary cylinder engines. This relative movement between pistons and cylinders is got by connecting the big ends of the connecting rods to, or forming them in the shape of, eccentric straps engaging either directly, or through interposed ball or roller bearings, with eccentric sheaves or bushes arranged to revolve on the crank pin at half the speed of the engine by means of 1 to 2 gearing. The eccentrics are set so as to give the requisite variations in the piston strokes at the desired periods, the maximum differentiation being usually but not necessarily between the end of the exhaust and beginning of the suction strokes and the end of the compression and beginning of the working strokes respectively.

The several eccentric sheaves are arranged to be fixed in proper relation to one another, on a bush, and the whole is clamped together

with the half speed gear wheel mounted on the crank pin, the bush running on the pin.

The gear wheel engages directly with a pinion which is conveniently fixed to one side of the crank case or is driven from it through an intermediate wheel, or by means of a chain drive. In the first case the centers of the connecting rod ends move in the opposite direction to that of the engine cylinders, and in the last two cases in the same direction but with a corresponding modification in the curve of the path of the pistons or connecting rod centers.

Instead of using separate ball bearings 70 the sheaves of the eccentrics may conveniently be made with a concave or flat groove to act as an inner race of a ball or roller bearing respectively. The big end of the connecting rod may also serve as the outer 75 race, in which case for convenience of assembling, the race may be flat or semi flat.

In order that the invention may be the better understood, I will now proceed to describe the same in relation to the accompanying drawings reference being had to the letters and figures marked thereon, like letters referring to like parts in the various figures, in which:—

Figure 1 is a part sectional view of a 7 85 cylinder engine constructed in accordance with my invention, but it is obvious that the shaft may also revolve in the opposite direction to the cylinders; Fig. 2 is a sectional view of the eccentric elements assembled on a common bush ready for mounting on the crank pin; Fig. 3 is an end view of the first element and bush flange; Figs. 4 and 5 are diagrammatic views of a 7 cylinder engine, showing the relation of pistons, connecting rods and cylinders at two phases of revolution of the engine separated by one complete revolution of the crank or engine, showing among other features the static and dynamic balance of all moving parts in spite of the 100 differential stroke conditions; Fig. 6 is a side view of one of the connecting rods, assembled on its sheave with rollers or balls interposed; and Fig. 7 is a part sectional view of an engine provided with a double 105 crank shaft having the operating gear for the sheaves on one crank pin so arranged as to transmit motion to the sheaves on the other crank pin.

As is usual in this type of engine, the casting ¹¹⁰ carrying the cylinders *b* is mounted on ball bearings *b'* and is adapted to revolve

about the axis of a stationary crank shaft c . Upon the crank pin d are mounted seven eccentric sheaves e assembled and fixed on a common bush f . The sheaves are made all alike and are provided with three holes each 5 ranged in a circle and pitched at $\frac{360^\circ}{n}$, where n = number of cylinders, by means of which they are assembled and fixed together 10 on the bush f in proper phase with one another.

The order of assembly of the sheaves on the bush corresponds with the order of firing of the cylinders with which they are associated and not with the geometric succession of the cylinders. This is indicated in Fig. 2 wherein the numerals on the sheaves indicate the geometric order of the cylinders and the order of these numerals represent 15 the order of firing of the cylinders. The fact that the centers of the sheaves are pitched $\frac{60^\circ}{n}$ apart and the cylinders taken 20 in order of firing $\frac{720^\circ}{n}$ conforms with required ratio of the speeds of revolution of 25 the cylinders and eccentrics, and as will be evident from inspection of Figs. 5 and 6 this arrangement also insures an even torque 30 perfect balance of the moving parts at all phases of revolution in spite of the differential movement of each individual piston.

Steady or driving pins j are driven 35 through the holes; each pin with the exception of the end pins being common to three sheaves see Figs. 2, 3 and 6. The seven sheaves together with the gear wheel k are finally locked on the bush by the tightening nut h . With the gear wheel k gears the 40 pinion l carried by the shaft m supported by bearing m' and attached at the opposite end to the crank case a or its extension at o preferably by means of a series of keys 45 formed integrally therewith and secured in place by the nut o' and distance bush o'' . The gear ratio of the wheel k and pinion l being 1 to 2 the sheaves e and therefore the centers of the big ends of the connecting rods receive a continuous motion in a circular path around the axis of the crank pin d at half the speed of the engine, as indicated diagrammatically in Figs. 4 and 5.

Referring to Figs. 4 and 5 the circle r represents the path of the center of each big 55 end of the connecting rod p about the axis of the crank pin d . The firing order of 1, 3, 5, 7, 2, 4, 6, is adopted, and the relative positions of the connecting rods p and pistons p' for this order of firing are shown 60 in the Figs. 4 and 5 as well as the influence of the differential stroke on the position of the pistons in the cylinders and the instantaneous position of the centers of the big ends of the connecting rods on the path 65 circle r .

In Fig. 4 the cylinder 7 and its piston are seen in the position of minimum clearance at the end of the exhaust stroke. In Fig. 5 the same cylinder and its piston are shown after the engine has made one complete revolution and it will be seen that the piston and cylinder are in the position of maximum clearance viz., at the end of the compression stroke. After one seventh of a revolution of the engine from the phase shown in Fig. 4, 70 the relation of No. 1 piston and cylinder will be the same as that of No. 7 cylinder and piston in the phase shown in Fig. 5, while the relation of piston and cylinder 2, after two sevenths of a revolution from the phase shown in Fig. 4 will be the same as 75 that of No. 7 cylinder and piston in that figure, and so on. This is clearly indicated on Figs. 4 and 5 by the lines I, II, III, IV, dividing the circle r into 4 quadrants C, W, 80 E, S, representing respectively the compression, working, exhaust and suction strokes. The location of the center of any given connecting rod in any quadrant directly indicates the phase of its piston and cylinder. 85

The axis of each cylinder b is preferably disposed relative to the casing a so as to coincide with the center line of the corresponding sheave e and the big end of the connecting rod p is arranged to surround 90 the sheave preferably with interposed rollers or balls q .

In Fig. 6 the connecting rod strap of big end n supports a ball or roller race n' in which balls or rollers n'' are disposed so 95 as to engage in the flanged race n^3 on the sheave e , which is the reverse arrangement to that shown in Fig. 2 in which the flanged race is on the strap or big end portion of the connecting rod.

In case it is desirable to have two or more sets of cylinders operating on a corresponding number of cranks, I may transmit the motion from the bush f Fig. 7, carrying one sheave or set of sheaves to the bush f' by 100 means of a wheel k' similar to k gearing with wheels l' l'' similar to l fixed on a common shaft t and transmitting the required motion to bush f'' by means of gear wheel k'' gearing with l'' . It is obvious that this 105 arrangement can be continued for any greater number of cranks than two.

Having thus fully described my invention, I claim as new and desire to secure by Letters Patent:—

1. A multicylinder four stroke internal combustion engine of the revolving cylinder type having in combination a rotatable crank case, an uneven number of cylinders alternately fired attached to said crank case, a plurality of pistons for said cylinders, a plurality of connecting rods for said pistons, a plurality of eccentric sheaves for said connecting rods, the said eccentric sheaves being symmetrically arranged in order that in con- 110

junction with alternate firing of the cylinders a static and dynamic balance of the moving parts and forces is obtained, a stationary crank shaft, a crank pin thereon, 5 adapted to carry said plurality of symmetrically arranged eccentric sheaves in a rotatable manner, a gear wheel attached to said plurality of symmetrically arranged eccentric sheaves and mounted rotatably on 10 said crank pin, a gear wheel attached to said rotatable crank case and meshing with the gear wheel on said crank pin, whereby a differential stroke movement is alternately added to and subtracted from the usual 15 relative movements of the pistons and cylinders.

2. A multicylinder four stroke internal combustion engine of the revolving cylinder type having in combination a rotatable crank case, a plurality of cylinders attached thereto and arranged in series, each series having an uneven number of alternately fired cylinders therein, a plurality of pistons for said cylinders, a plurality of connecting rods for said pistons, a plurality of eccentric sheaves for said connecting rods, arranged in series numerically similar to the series of cylinders, the said eccentric sheaves in each series being symmetrically arranged 25 in order that in conjunction with alternate firing of the cylinders correlated thereto a static and dynamic balance of the moving parts and forces is obtained, a stationary crank shaft, crank pins thereon adapted to 30 carry said plurality of symmetrically arranged eccentric sheaves in a rotatable manner, gearing attached to each series of eccentric sheaves and rotatably mounted on one of said crank pins, a gear wheel attached 35 to said rotatable crank case and meshing with the gearing on one of said crank pins and gearing arranged between each series of eccentric sheaves to transmit the motion 40 from one series to the next, whereby a differential stroke movement is alternately added to and subtracted from the usual relative movements of the pistons and cylinders.

3. A multicylinder four stroke internal combustion engine of the revolving cylinder type having in combination, a rotatable crank case, an uneven number of cylinders alternately fired attached to said crank case, 50 a plurality of pistons for said cylinders, a plurality of connecting rods for said pistons, a plurality of eccentric sheaves for 55 tons, a plurality of eccentric sheaves for

said connecting rods, the said eccentric sheaves being symmetrically arranged in order that in conjunction with alternate firing of the cylinders a static and dynamic balance of the moving parts and forces is obtained, a stationary crank shaft, a crank pin thereon, a sleeve rotatably mounted on 60 said crank pin, a gear wheel attached to said rotatable sleeve and a plurality of symmetrically arranged eccentric sheaves which are mounted thereon, a gear wheel attached to said rotatable crank case and meshing with the gear wheel on said crank pin, whereby a differential stroke movement is alternately added to and subtracted from 70 the usual relative movements of the pistons and cylinders.

4. A multicylinder four stroke internal combustion engine of the revolving cylinder type having in combination a rotatable crank case, a plurality of cylinders attached thereto and arranged in series each series having an uneven number of alternately fired cylinders therein, a plurality of pistons for said cylinders, a plurality of connecting rods for said pistons, a plurality of eccentric sheaves for said connecting rods arranged in series numerically similar to the series of cylinders, the said eccentric sheaves in each series being symmetrically arranged 80 in order that in conjunction with alternate firing of the cylinders correlated thereto a static and dynamic balance of the moving parts and forces is obtained, a stationary crank shaft, crank pins thereon, sleeves rotatably mounted on said crank pins, gearing attached to each sleeve on which are mounted a series of eccentric sheaves, a gear wheel attached to said rotatable crank case and meshing with the gearing on one of said 85 crank pins and gearing arranged between each series of eccentric sheaves to transmit the motion from one series to the next, whereby a differential stroke movement is alternately added to and subtracted from 90 the usual relative movements of the pistons and cylinders.

In testimony whereof I have signed my name to this specification in the presence of two subscribing witnesses.

JOSEPH ZEITLIN.
